SWITCH CONTROL MECHANISM

Filed Aug. 4, 1926

UNITED STATES PATENT OFFICE.

FRANK H. CUSHING, OF LOUISVILLE, KENTUCKY.

SWITCH-CONTROL MECHANISM.

Application filed August 4, 1926. Serial No. 127,106.

This invention relates to certain novel and useful improvements in switch control mechanism and more particularly to a control mechanism intended for use in connection with electrically driven tools and particularly adapted for use in connection with portable electrically driven reamers and drilling machines and the like.

One of the many objects of the invention is to simplify the general construction of the mechanism controlling the circuit switch of the electrically driven tool and to avoid the use of complicated and delicate machinery.

A further object of the invention is to provide mechanism of this character which can be expeditiously operated by the finger of the operator without releasing his hold upon the tool thereby greatly facilitating manual manipulation of the electrically driven tool.

20 A further object of the invention is the provision of mechanism of this character which has but a single one way operating trigger for optionally opening or closing the circuit switch of an electrically operated tool.

25 Other objects will appear hereinafter.

The invention consists in the combination and arrangement of parts to be hereinafter described and claimed.

The invention will be best understood by reference to the accompanying drawing illustrating the preferred form of construction, and in which:

30 Fig. 1 is a side elevational view of an electrically driven tool showing the handle portion thereof broken away to illustrate the application of the invention therewith.

Fig. 2 is a fragmentary side elevational view of the mechanism, embodied in the invention, for controlling the circuit switch.

40 Fig. 3 is an elevational view showing my improved mechanism operatively connected with a circuit switch of a well known type used in connection with electrically driven tools.

45 Fig. 4 is a perspective view of a carriage plate embodied in the invention.

Fig. 5 is a fragmentary edge view of the invention taken substantially on line 5—5 of Fig. 2.

50 As herein indicated it is an object of this invention to provide control mechanism of this character whereby the operator of the electrical drill need not, to operate the control mechanism, release his grip from the handle of the electrical tool thereby enabling

the operator to expeditiously manipulate the tool.

To accomplish this and other objects of the invention I have illustrated in the drawing an electrical tool A including among other 60 things a chuck B for holding the drill or the like and a handle portion C which is in most instances hollow in construction. Confined within this handle portion C is my improved control mechanism D which controls the circuit switch E which controls the electrical circuit to the motor (not shown) of the tool A.

This circuit switch E is of any approved construction which includes a circuit breaker 70 arm 10 pivotally supported as at 11 by a supporting structure 12 which is operable by an operating handle 13. This handle 13 includes a knob shaped end portion 14 and is pivotally connected to the structure 12 as at 75 15. The operating handle 13 is operatively connected to the breaker arm 10 through the medium of a spring control rod 16 whereby when the operating handle 13 is pivoted in a direction about the pivot 15 the spring 17 80 of the rod 16 will act upon the breaker arm 10 and pivot this breaker arm 10 into contact with the conductor fingers 18 of the circuit switch E.

The circuit switch E is not included as a 85 part of my invention and I therefore have illustrated an approved circuit switch to demonstrate the application of my invention as at this time it is pointed out that any type of circuit switch may be employed which includes a pivotally mounted operating handle 90 as indicated at 13.

Secured to the handle portion C through the medium of screw members 19 is a carriage plate 20 defining at one end portion 21 spaced 95 lateral projections 22 and at an opposite end portion an extension 23 and a single lateral projection 24. Pivotally associated as at 25 with the carriage plate 20 is an oscillatory member or lever 26 connected at one end as at 100 27 to a connecting rod 28 which rod is connected as at 29 to the knob 14 of the operating handle 13. This oscillatory member defines at its pivot end portion a two-toothed ratchet head 30.

The carriage plate 20 has struck therefrom a guide loop 31 and secured to this guide loop 31 as at 32 is a spring member 33 having an end portion connected as at 34 to the oscillatory member 26. This spring member 110

functions to complete final oscillatory movement of the member 26 in either direction about the pintle 25, it being pointed out that the connection 34 is offset relative to the pivot 5 connection 25.

Pivottally connected to the extension 23, as at 35, is an operating trigger 36 defining a finger engaging portion 37. This operating trigger is substantially bell crank shaped and its limb portion 38 is pivottally connected as at 39 intermediate the end portions of a pawl 40. This pawl 40 is movable beneath the guide loop 31 in a direction along its length into engagement with either of the teeth 41 10 of the ratchet head 30. Movement in one direction of the pawl 40 is controlled by a spring member 42 having one end portion connected as at 43 to the carriage plate and an opposite end portion connected as at 44 15 to the adjacent end portion of the pawl 40.

Movement of the operating trigger in one direction is accomplished through the medium of the pawl 40 when moved in the same direction by the action of the spring 42 and 20 this operating trigger is limited in movement in said one direction by the projection 24.

The oscillatory member 26 is likewise limited in its oscillatory movement by means of the lateral projections 22 as best shown in 30 Fig. 4.

The finger engaging portion 37 of the operating trigger 36 projects through an elongated slot 45 formed in a wall portion 46 of the handle portion C.

To operate the control mechanism, the operator having his hand in firm grasping relation with the handle C presses one finger against the finger portion 37 to pivot the operating trigger about its pivot 35. This pivotal movement of the operating trigger 36 acts upon the pawl 40 and moves this pawl in a direction to engage the tooth of the teeth 41 of the ratchet head disposed in the path of movement of the pawl. When the end portion 41' of the pawl 40 is brought into engagement with this tooth the member 26 is urged to pivot about the pivot point 25 by continued movement of the pawl 40 and operating trigger 36. Final movement of the member 26 is completed by action of the spring member 38. Pivotal movement of the member 26 by action of the pawl 40 acts upon the connecting rod 28 to move this connecting rod in the direction of pivotal movement of the oscillatory lever 26 and this connecting rod in turn acts upon the handle 13 and pivots this handle 13 in the direction of pivotal movement of the oscillatory member or lever 26 closing or opening the circuit as the case 50 may be. After this has been accomplished the operator releases his finger from the operating trigger 37 and this operating trigger is returned to its normal position as is likewise the pawl 40 by action of the spring 42. 55 By repeating this operation the pawl 40 will

be moved into engagement with the other of the teeth 41 now disposed in the path of movement of the pawl.

From the above description it is manifest that I provide a simple combination and arrangement of parts for controlling the circuit switch used in connection with electrically driven tools and that by the use of such mechanism the operator is in position to manually operate the control mechanism without releasing his grip from gripping relation with respect to the handle portion C. 70

While I have illustrated and described the preferred form of construction for carrying my invention into effect, this is capable of variations and modification without departing from the spirit of the invention. I, therefore, do not wish to be limited to the precise details of construction set forth, but desire to avail myself of such variations and modifications as come within the scope of the appended claims. 80

Having thus described my invention, what I claim as new and desire to protect by Letters Patent is:

1. A mechanism of the class described including a carriage plate, an operating trigger pivottally carried by the carriage plate, a pawl pivottally connected to an end portion of the operating trigger and movable along its length in one direction by operation of the trigger, means for moving the pawl in an opposite direction, a member pivottally carried by the carriage plate and having at one end a two-toothed ratchet adapted for engagement by the pawl for oscillating said member about its pivot connection with the carriage plate, and resilient means for completing final pivotal movement of the member in either direction about its pivotal connection with the carriage plate. 90

2. A mechanism of the class described including a carriage plate, an operating trigger pivottally carried by the carriage plate, a pawl pivottally connected to an end portion of the operating trigger and movable along its length in one direction by operation of the trigger, means for moving the pawl in an opposite direction, a member pivottally carried by the carriage plate and having at one end a two-toothed ratchet adapted for engagement by the pawl for oscillating said member about its pivot connection with the carriage plate, a spring member inserted through an opening formed in said member and having opposite end portions connected to the carriage plate, said spring member serving to complete final pivotal movement of the member in either direction about its pivotal connection with the carriage plate. 100

3. A mechanism of the class described including a carriage plate, an operating trigger pivottally carried by the carriage plate, a pawl pivottally connected to an end portion of the operating trigger and movable along

its length in one direction by operation of the trigger, means for moving the pawl in an opposite direction, a member pivotally carried by the carriage plate and having at one end a two-toothed ratchet adapted for engagement by the pawl for oscillating said member about its pivot connection with the carriage plate, a spring member inserted through an opening formed in said member, and having opposite 10 end portions connected to the carriage plate, said spring member serving to complete final pivotal movement of the member in either direction about its pivotal connection with the carriage plate, means for guiding said 15 pawl during its movement toward operative engagement with either of the teeth.

4. A mechanism of the class described including a carriage plate having at one end portion spaced lateral projections and at the 20 opposite end portion a single lateral projection, an operating trigger pivotally carried by the carriage plate and limited in its pivotal movement in one direction by the single lateral projection, an oscillatory member pivotally 25 carried by the carriage plate and limited in its pivotal movement by the spaced lateral projections, said oscillatory member having at one end a two-toothed ratchet head, a pawl pivotally connected to the trigger intermediate its end portions and movable in a direction along its 30 length to engage one end portion with either of the teeth of the ratchet head whereby to oscillate said oscillatory member, and a spring having one end connected to the carriage plate and the opposite end connected to the pawl for moving said pawl in an opposite direction along its length.

teeth of the ratchet head whereby to oscillate 35 said oscillatory member, resilient means for completing initial oscillatory movement of the oscillatory member in either direction about its pivotal connection with the carriage plate, and a spring having one end connected to the carriage plate and an opposite end connected 40 to the pawl for moving said pawl in an opposite direction along its length.

5. A mechanism of the class described including a carriage plate having at one end portion spaced lateral projections and at the 45 opposite end portion a single lateral projection, a bell crank shaped operating trigger pivotally carried by the carriage plate and limited in its pivotal movement in one direction by the single lateral projection, an oscillatory member having at one end a two-toothed ratchet head, a pawl pivotally connected to the trigger intermediate its end portions and movable in a direction along its 50 length to engage one end portion with either of the teeth of the ratchet head whereby to oscillate said oscillatory member, and a spring having one end connected to the carriage plate and the opposite end connected to the pawl for moving said pawl in an opposite direction along its length.

In testimony whereof I affix my signature.
FRANK H. CUSHING.
